US0D1057616S

(12) **United States Design Patent** (10) Patent No.: **US D1,057,616 S**
(45) Date of Patent: ** Jan. 14, 2025

(54) **AIR INTAKE GRILLE FOR MOTOR VEHICLE**

(71) Applicant: **Dr. Ing. h.c. F. Porsche Aktiengesellschaft**, Stuttgart (DE)

(72) Inventor: **Fabian Schmölz**, Stuttgart (DE)

(73) Assignee: **Dr. Ing. h.c. F. Porsche Aktiengesellschaft** (DE)

(**) Term: **15 Years**

(21) Appl. No.: **29/860,729**

(22) Filed: **Nov. 22, 2022**

(30) **Foreign Application Priority Data**
